UNITED STATES PATENT OFFICE

OTTO W. HAMBURG, OF SAN DIEGO, CALIFORNIA

COLLAPSIBLE CHAIR

Application filed May 25, 1929. Serial No. 366,020.

My invention relates to collapsible chairs, and the objects of my invention are: first, to provide a chair of this class which when collapsed is light, compact, and easy to carry; second, to provide a chair of this class which when open is rigid and sturdy enough to stand hard use; third, to provide a chair of this class which may be used as a folding beach chair by omitting the legs; fourth, to provide a chair of this class whereby the back and legs fold across the seat of the chair and are confined substantially within the margins of said seat; fifth, to provide a chair of this class which is easily stacked for storage or the like; sixth, to provide a chair of this class which requires no tools for folding or unfolding it; seventh, to provide a novel means of interlocking the back and rear leg portions of a chair so that when said chair is open said back and leg portions are held in rigid relation to each other and to the seat, and eighth, to provide on the whole a novelly constructed, collapsible chair, which is durable, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a perspective view of my chair when in its open position; Fig. 2 is another perspective view thereof showing it in its collapsed position; Fig. 3 is a perspective view of my chair used as a beach seat; Fig. 4 is a perspective view of the hinge and brace means for holding the rear legs and back relative to the seat; Fig. 5 is a fragmentary side elevational view of my chair with parts and portions in section to facilitate the illustration; Fig. 6 is a fragmentary enlarged elevational view of one of the brace members; Fig. 7 is a transverse sectional view thereof through 7—7 of Fig. 6; Fig. 8 is a reduced fragmentary rear elevational view

of my chair; Fig. 9 is an enlarged fragmentary sectional view through 9—9 of Fig. 5, and Fig. 10 is a fragmentary bottom view showing my chair in its collapsed position.

Similar characters of reference refer to similar parts and portions throughout the several views of the drawings.

Seat member 1, hinge members 2 and 3, back member 4, rear legs 5, stop members 6, front leg hinges 7, front legs 8, rungs 9, folding braces 10, tie braces 11, rear leg braces 12, and handles 13 and 14, constitute the principal parts and portions of my collapsible chair.

The seat 1 has substantially the dimensions of a conventional chair seat and consists of a substantially rectangular frame 1a with slats 1b connecting the front and rear portions, as shown best in Fig. 1.

Hinge members 2 and 3 support a back member relative to the seat 1. Each hinge member 2 comprises a saddle portion 2a which is substantially U-shaped in cross-section and straddles the rear end of a side member 1c. The leg portions 2b project past the inner margin of the side member 1c and over the end of the rear cross member 1d of the seat frame 1a. The cross portion 2c of the saddle portion 2a which connects the legs 2b thereof extends past the rear edge margin of the leg portion 2b of the saddle and is provided with two ear portions, one extending upwardly and the other extending downwardly. The upwardly extending ear portion 2d forms a hinge element for supporting the chair back member 4. The downwardly extending ear 2e forms a hinge element for supporting one of the rear legs 5 of the chair.

The hinge members 3 are substantially T-shaped, the leg 3a of which is adapted to extend between the edge of the rear frame member 1d and adjacent side portion of the corresponding frame side member 1c and is held in such position by screws extending from the cross portion 2c of the saddle 2a through the side members of the frame 1a into the end of the rear frame member, as shown best in Fig. 9. The extended portions 3b and 3c of the hinge member 3 which form

the cross portion of the T are similar to the ear portions 2d and 2e and are in spaced aligned relation thereto. These extended portions 3b and 3c form the other hinge elements 5 for supporting the back 4 and rear legs 5, respectively, of the chair.

The back member 4 of the chair consists of two upright members 4a and transversely extending slat members 4b connecting said uprights. The lower end of each upright member 4a is pivotally mounted between the ear portion 2d and the extended portion 3b of the hinges 2 and 3. The pivotal points of the upright members 4a are far enough above the upper surface of the seat 1 so as to permit the back to fold flat against the seat, as shown in Fig. 2. The portion of each upright member 4a below the pivotal point thereof extends past the rear edge of the seat frame and forms a stop 4c, as shown in Figs. 2 and 5, which engages the seat 1 and limits the rearward movement of the back member 4 relative thereto.

Pivots mounted by its upper end between each lower ear portion 2e and its corresponding lower extended portion 3c is a rear leg member 5. Secured to the back of each leg member and projecting upwardly from the rear side thereof is a stop member 6, which consists of a flat piece of material adapted to bear against the rear side of the stop portion 4c of the upright 4a when the chair is in its open position shown in Figs. 1 and 5. Thus when the chair is open the back member 4 cannot move rearwardly because of the stop portion 4c and cannot move forwardly because of the stop member 6.

Secured to the under side of the forward cross member 1e of the seat frame just within the inner margin of the side members of said frame is a pair of front leg hinges 7. Each hinge 7 is substantially U-shaped and secured by its cross portion to the under side of the seat frame with its leg portions extending downwardly. Pivots mounted between these leg portions of each hinge so as to swing into flat adjacent relation to the seat 1 is a front leg 8. Rungs 9 extend between the two front legs 8 so as to hold them in proper spaced relation to each other.

Folding braces 10 are adapted to hold the front and rear legs in proper extended relation to the seat 1 and to each other. One pair A of these braces extend from the front legs upwardly and rearwardly to the inner edge of the side members 1c of the seat frame 1a. A second pair B of folding braces 10 extend from this point rearwardly and downwardly to the inner sides of the rear legs 5. A third pair C of folding braces 10 may provided which extend between the front and rear legs joining said legs at the same place as the first and second folding braces. Each folding brace 10 consists of two arm members 10a and 10b. Each arm member 10a is pro-

vided with a transversely extending offset portion which when folded against the arm forms a longitudinally extending channel 10c of U-shaped cross section. The arm 10b of each folding brace 10 is adapted to extend into the channel 10c and is pivotally connected to the arm 10a by a rivet 10d extending transversely through the channel. The channel 10c limits the movement of one arm relative to the other so that the brace can only be collapsed by bending it towards the pivotal point of the respective legs with the seat 1. In order to prevent accidental buckling when the chair is in open position, a tie brace 11 extends between the corresponding brace members 10 of the brace pairs A and B.

Each tie brace 11 is pivotally connected to one member of the folding brace pair B and is provided with a notch 11b in the under side of its extended edge which is adapted to engage a portion 10e of the rivet shank, as shown in Figs. 6 and 7.

The brace pair C assists the action of the tie brace 11 and is similar to the other pairs A and B of the folding braces 10 except that a notch 10f is provided at their one ends for engaging the shank supporting the brace pair A relative to the front legs 8.

The rear legs 5 are held in proper relation to one another by rear leg braces 12, as shown in Fig. 8.

Each rear leg 5 is adapted when folded to lie flat against the under side of the seat member 1 flush with the outer edge of its corresponding side member 1c, as shown best in Fig. 10. Each front leg 8 when folded rests against the under side of the corresponding side member 1c in spaced relation to the corresponding rear leg 5. The legs 5 and 8 are tapered so that there will be sufficient space between them to receive the folding braces 10 and tie brace 11 when they are in their folded position, shown in Fig. 10.

The chair is folded as follows: The tie braces 11 and sets C of the folding braces 10 are released, then the folding braces 10 of the brace set A are folded permitting the front legs to collapse against the under side of the seat. In a similar manner the brace set B is folded permitting the rear legs to collapse against the under side of the seat so that the bracing 12 thereof extends across the front legs 8 and holds them in their folded position, as indicated in Fig. 10. Lastly the back member 4 is folded across the top of the seat, the stops 6 having been moved out of engagement with the back 4 when the rear legs 5 were collapsed.

A handle 13 is provided on a rear leg 5 and a handle 14 is provided on one of the uprights 4a so that when the chair is folded to the position shown in Fig. 2, the handles are opposite one another and may be grasped together by one hand. When the two handles are grasped the chair is held in its folded

position and cannot accidentally open up unless the handles are released.

The structure shown in Fig. 3 is similar to the hereinbefore described structure except that the ears $2e$ of the hinges 2 and the projections $3c$ of the hinges 3 are removed together with the hinges 7 , rear legs 5 , front legs 8 , and bracing therefor. In this case the handle 13 is placed on the side of the seat 1 , as shown in Fig. 3.

It is obvious from the construction as illustrated in the drawings and described in the foregoing specification, that there is provided a collapsible chair as set forth in the objects of the invention, and though I have shown and described a particular construction, combination and arrangement of parts and portions, and a certain modification thereof, I do not wish to be limited to this particular construction, combination and arrangement, nor to the modification, but desire to include in the scope of my invention the construction, combination and arrangement substantially as set forth in the appended claims.

Having thus described my invention, what I claim as new and desire to secure by Letters Patent is:

1. In a collapsible chair, a chair seat, a pair of hinge elements having saddle portions connecting the rear and side portions of said chair seat, a second pair of hinge elements, each supported in spaced relation to a hinge portion of each first hinge element by the members of said chair seat joined by said saddle portions, and a back member pivotally connected with its corresponding first and second hinge elements and adapted to fold against said seat.

2. In a collapsible chair, a chair seat, a pair of hinge elements having saddle portions connecting the rear and side portions of said chair seat, a second pair of hinge elements each supported in spaced relation to a hinge portion of each first hinge element by the members of said chair seat joined by said saddle portions, a back member pivotally connected with its corresponding first and second hinge elements and adapted to fold against said seat, and stop means for limiting rearward pivotal movement of said back member.

3. In a collapsible chair, a chair seat, a pair of hinge elements having saddle portions connecting contiguous rear and side portions of said chair seat, a second pair of hinge elements each supported in spaced relation to a hinge portion of each first hinge element by the members of said chair seat joined by said saddle portions, a back member having side portions pivotally connected with their corresponding first and second hinge elements and adapted to fold against said seat, handle means secured to the central portions of contiguous side portions of said back and seat equidistant relative to the piv-

otal point of said side portion, whereby when collapsed, said handles are positioned side by side and when jointly grasped hold said back and seat in folded relation.

4. In a collapsible chair, a chair seat member comprising a frame and a seat portion, a pair of saddle means connecting the side and rear members of said frame, a hinge element integral with each saddle extending rearwardly of said frame, a second pair of hinge elements, each having a portion thereof positioned between an end of the back member of said frame and the adjacent portion of the corresponding side member of said frame and secured in said position by means holding said saddles, each of said second pair of hinge elements extending in spaced relation to a corresponding first hinge element, and a chair back pivotally supported by said first and second hinge elements, said chair back adapted to fold against said chair seat.

5. In a collapsible chair, a chair seat member comprising a frame and a seat portion, a pair of saddle means connecting the side and rear members of said frame, a hinge element integral with each saddle extending rearwardly of said frame, a second pair of hinge elements, each having a portion thereof positioned between an end of the back member of said frame and the adjacent portion of the corresponding side member of said frame and secured in said position by means holding said saddles, each of said second pair of hinge elements extending in spaced relation to a corresponding first hinge element, a chair back pivotally supported by said first and second hinge elements, said chair back adapted to fold against said chair seat, and handle means secured to mutually foldable portions of said chair, said handles adapted to lie side by side when said chair is collapsed and when jointly grasped, to hold said chair in folded position.

6. In a collapsible chair, a chair seat member comprising a frame and a seat portion, a pair of saddle means connecting the side and rear members of said frame, a hinge element integral with each saddle extending rearwardly of said frame, a second pair of hinge elements, each having a portion thereof positioned between an end of the back member of said frame and the adjacent portion of the corresponding side member of said frame and secured in said position by means holding said saddles, each of said second pair of hinge elements extending in spaced relation to a corresponding first hinge element, a chair back pivotally supported by said first and second hinge elements, the lower end of the side members of said chair back terminating flush with the lower surface of the seat, said chair back adapted to fold against said chair seat, a pair of chair legs pivotally connected with said first and second hinge elements, their upper ends in abutment with the

lower ends of said side members, and adapted to shift into folded relation with said chair seat, an extension strap on the upper end of said legs overlapping the lower end of said side members, and a second pair of legs pivotally supported at the forward portion of said chair seat and adapted to shift into folded relation with said chair seat.

5 In testimony whereof, I have hereunto set
10 my hand at San Diego, California, this 18th
day of May, 1929.

OTTO W. HAMBURG.
